UNITED STATES PATENT OFFICE

JOHN C. GARAND, OF SPRINGFIELD, MASSACHUSETTS

FOLLOWER

Application filed March 31, 1931. Serial No. 526,665.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a follower intended primarily for use in firearms provided with a magazine adapted to receive a double row of cartridges in staggered relation.

The main objects of this invention are the provision of a follower which permits a double column cartridge clip to be used in which either the right hand or left hand column of cartridges may be uppermost; which, consequently, does not require that the user load 10 the clip having the uppermost or lowermost cartridge on a particular side; which permits the loading of an odd or even number of cartridges in a double column into the magazine, and, if the cartridges are held in a clip, 15 permits the feeding of the clip into the magazine either end first; which permits the use of a cartridge clip for a double column of cartridges having both ends alike.

To these ends the invention resides broadly in a follower provided with an element to be contacted by the lowermost cartridge of a double column of cartridges to cause such a repositioning of the upper surface of the follower that the concave surface of the follower 25 lower adapted to receive the lowermost cartridge will lie to the right or left respectively as the lowermost cartridge lies to the right or left.

Specifically, this invention may find its embodiment in a follower tiltable about a longitudinal axis; or in a follower the central longitudinal portion of the upper surface of which is shiftable transversely of the follower; or in a follower shiftable transversely.

40 The invention is shown by way of illustration in the accompanying drawings, wherein:

Fig. 1 is a fragmentary view in longitudinal section of a portion of a firearm containing a magazine and showing the follower therein in side elevation;

Fig. 2 is a plan view of the follower, fragments of the side walls of the magazine being shown in section;

50 Fig. 3 is a bottom view of the follower;

Fig. 4 is a cross section on the line 4-4 of Fig. 2;

Fig. 5 is a plan view of the follower arm;

Fig. 6 is a side elevation of the same;

Fig. 7 is a rear end view of the follower;

55 Fig. 8 is a plan view of another form of follower, fragments of the receiver shown in section;

Fig. 9 is a front elevation of the same;

Fig. 10 is a sectional view taken on the line 10-10 of Fig. 8, the portions of the receiver omitted;

Fig. 11 is a longitudinal section view;

60 Fig. 12 is a sectional view taken on the line 12-12 of Fig. 11;

Fig. 13 is an end elevation of still another form of follower, a clip being shown partly in end elevation and partly in section;

Fig. 14 is a similar view illustrating another position of the follower;

70 Fig. 15 is a plan view of the follower;

Fig. 16 is a side elevation of the same.

Referring to the drawings by numerals of reference:

75 A fragment of a firearm is shown provided with a stock 5, and receiver 6, to which is secured the barrel 7, and in which is reciprocally mounted on bolt 8. The firearm is provided with a follower rod 9, actuated by resilient means, not shown, to raise the follower 80 and feed cartridges upwardly through the magazine 10 to position to be contacted by the bolt 8 as it moves forward to breech closing position.

85 A follower arm 11 is mounted on a pivot 12 in the receiver and is formed with laterally projecting studs 13, adapted to be engaged in recessed forked ends on the follower rod 9. The follower engaging end of the follower arm 11, is adapted for sliding engagement with the follower in any convenient manner, the specific form herein illustrated consisting in a T head 14 having a sliding fit in a T slot 15 formed in the follower 16. 90 The dimensions of the T slot 15 are such that the follower is allowed considerable lateral play on the head 14 of the follower arm.

95 The follower may be formed with a central longitudinal rib 17, of sufficient height to be 100

contacted by the lowermost cartridge of a double stack of cartridges.

The upper surface of the follower at either side of the rib is preferably concave to conform to the contour of a cartridge case. The follower is provided with laterally extending flanges 18 adapted to engage in guide grooves 19 formed in the side walls of the magazine. For the purpose of reducing friction rollers 10 20 may be mounted on the flanges 18.

The form of follower shown in Figs. 8 to 12 inclusive, is similar to the follower hereinbefore described, except that in this case the upper portion 21 of the follower containing the central rib and concave portions is made as a separate piece provided near its rear end with a depending hooked stud 22 adapted to enter an aperture 23 formed in the base 24 of the follower with its hooked portion underlying the bottom surface of the base. Near its forward end the upper portion has a depending transverse rib 25 which enters a slot 26 formed transversely of the base. From a consideration of the structure just described it is evident that the upper portion 21 of the follower is adapted to slide transversely of the base. The case in this instance may be formed with flanges 27 adapted to enter the grooves 19 formed in the receiver. 25 30

In the form of follower shown in Figs. 13 to 16, inclusive the base 27 is the same as hereinbefore described with the exception that it is provided with means, specifically the apertured lugs 28-28, for pivotally mounting on the base an upper portion 29 so formed that when tilted to one side or the other about its pivot the up tilted or high side will form an upper step and the down tilted side will be in position to form a lower step. 35 40

The operation of the device is as follows: Where cartridges are fed into the magazine the lowermost cartridge will contact the rib 17 causing the rib to slide transversely of the follower, or causing the follower to slide transversely, as the case may be, thus positioning the concave surface to receive the lowermost cartridge. In the case of the pivoted follower the lowermost cartridge engages the follower to one side or the other of the pivoted axis thus causing the follower to rock to proper position to elevate the stack of cartridges during feeding operation. 45 50

I claim:

55 1. A receiver, a magazine formed in the receiver, guide grooves in the side walls of the receiver, a follower in the magazine mounted for lateral movement, elements on the follower engaged in the guide grooves, a 60 follower arm pivotally mounted in the receiver and having a loose connection with the follower, means on the follower contacted by the lowermost cartridge of a clip containing a double row of cartridges in staggered relation to shift the follower later- 65

ally, and means engaging the follower arm to operate the follower to feed cartridge upwardly to loading position.

2. A follower for the magazine of firearms adapted to receive a double row of cartridges in staggered relation embodying an element on the follower adapted to occupy either a central, or right hand, or left hand position, contacted by the lowermost cartridge and moved thereby from any of its positions to position the upper surface of the follower to accommodate itself to the lowermost cartridges. 75

3. A follower for the magazine of firearms adapted to receive a double row of cartridges in staggered relation embodying an element on the follower adapted to occupy either a central, or right hand, or left hand position, contacted by the lowermost cartridge and moved thereby from any of its positions to change the position of the upper surface of the follower to accommodate itself to the lowermost cartridges. 80

4. In a magazine rifle adapted to receive a double row of cartridges in staggered relation, a follower arranged to be moved by contact with the lowermost cartridge from normal central position to right or left hand position, or from right hand position to left hand position or the reverse to provide either a right or left hand concave surface for engaging the lowermost cartridge of said stack. 85

5. In a magazine rifle adapted to receive a double row of cartridges in staggered relation, a follower providing a movable step which is automatically shifted from right to left hand position or the reverse by its engagement with the bottom of said stack. 90

6. In a magazine rifle adapted to receive a double row of cartridges in staggered relation, and a follower for said cartridges movable from right to left hand feed or the reverse by engagement with the cartridges. 95

7. In a magazine rifle adapted to receive a double row of cartridges in staggered relation, a follower for said cartridges, and an upper step disposed centrally thereof, and adapted to be engaged by the bottom cartridge to shift the follower to a right or left hand position or from right hand to left hand position or the reverse. 100 110 115

JOHN C. GARAND.
